(57) **CLAIM**

The ornamental design for a seat, as shown and described.

DESCRIPTION

FIG. 1 is a left front perspective view of a seat showing my new design;

FIG. 2 is a front elevational view thereof;

FIG. 3 is a side elevational view, the opposite side being a mirror image thereof;

FIG. 4 is a rear perspective view thereof; and,

FIG. 5 is a top view thereof.

The bottom view is not shown and forms no part of the claimed design. The dashed lines represent environmental elements only and form no part of the claimed design.
